EXPLOSIVE ASSEMBLY

Cyril J. Breza, Mickleton, and Charles H. Noren, Woodbury, N. J., assignors to E. I. du Pont de Nemours and Company, Wilmington, Del., a corporation of Delaware

Application November 30, 1953, Serial No. 395,075

6 Claims. (Cl. 102—24)

The present invention relates to an explosive assembly. More particularly, it concerns a column of connected explosive cartridges.

In many types of blasting operations, the preferred method of introducing the explosive cartridges into the blasting zone is in the form of a column. This involves connecting a plurality of cartridges end to end. A number of connectors for this purpose are known, most of them being in the nature of a sleeve having internal gripping means and being adapted to receive a cartridge at either end. Such connectors form a rigid column and are satisfactory when deformable. When the explosive composition in the cartridge is not deformable however the gripping means of the sleeve type connector cannot secure a good hold. Furthermore, the sleeve connectors are both expensive and bulky.

It is an object of the present invention to provide an explosive assembly in column form wherein the connecting means can be used with non-deformable explosive cartridges.

Another object is to provide an assembly involving a plurality of cartridges connected end to end wherein the connecting device does not increase the diameter of the column.

These and other objects will become apparent in the course of the following specification and claims.

The foregoing object is achieved by providing a plurality of substantially cylindrical cartridges joined end to end by connecting means comprising a cartridge anchored ribbon loop joined by a connecting link having helical or open loop ends. The helices are substantially parallel to each other. They lie in the same plane relative to the straight section of the connecting link. They are preferably so wound that their ends lie on opposite sides of the straight section.

In order to more fully describe this invention, reference is made to the accompanying drawings in which:

Figure 1 represents a side view of the connector employed in the present invention;

Figure 2 represents a top view of the connector illustrated in Figure 1;

Figure 3 represents an explosive cartridge with a bail attached; and

Figure 4 represents a column of explosive cartridges connected in accordance with this invention and positioned within a borehole.

Figure 1 is a side representation of the connecting body 1 having helical ends which is used as the link in the connecting means. As can be seen from the drawing the helices lie in the same plane relative to the connecting body. A top view of the structure, shown in Figure 2, shows that the helices are parallel to each other. In the preferred embodiment they terminate on opposite side of the straight section which separates the helices.

The material of construction of the connecting link is not critical. Wire, such as for instance 70 mil steel wire, is preferred. The helices may be formed by a single

2

coil as shown or multiple coils. Multiple coils may be voluted or adjacent turns may lie side by side.

Figure 3 illustrates an embodiment of the anchored loop portion of the connecting means. Here a bail is provided by attaching a half loop of ribbon of fabric 2 to the end of an explosive cartridge 4 by means of a retaining strip 3. The anchored bail may be provided by other means such as by adhesively fastening a loose strip over the ends of a cartridge or by an extension of the outer walls of the cartridge in the form of a loop. Alternatively the cartridge may be enclosed in a bag or net which provides loops at either end. The bail may be a tape or ribbon of any material having sufficient strength. A fabric, such as cotton duck, or metal, plastic or the like may be employed. A pressure sensitive tape is preferred since in this structure other bonding means to the cartridge is unnecessary. Where the bail is bonded to the cartridge by a retaining strip, this may be of the pressure sensitive type. Other adhesive may also be used to anchor the retaining strip.

Figure 4 illustrates the explosive assembly in column form positioned within a borehole 5 and supported by lowering line 6. In this figure, the bail is a loose strip 7 fastened directly to the cartridge over its end. The column is formed by pulling the bail of adjacently positioned cartridges into opposite helices of a connecting link.

The column thus formed is sufficiently flexible to permit loading into a rough or irregular borehole, and the cartridges are all maintained in a column form. In the event one or more cartridges become temporarily wedged in the borehole while cartridges above continue to be lowered, the connection will not be lost since the bail will flatten and will remain within the loops of the connecting link. It will be readily appreciated that the release of one or more cartridges during loading introduces a hazard of premature explosion due to the uncontrolled drop, and also destroys the desired column formation.

As mentioned previously, the connecting link is preferably fabricated from a metal wire. It must have sufficient strength to retain its shape under the predetermined load of the explosive column. The helices are angled from the straight section to the extent necessary to provide an opening of sufficient size for easy insertion of the bail. Where a single loop is employed to form the helix, its end should extend at least to the starting point of the straight section thereby slightly overlapping to prevent the bail from being dislodged if the column becomes wedged. The connector will normally have a length of from one to two inches, and the loop a diameter of about $\frac{1}{2}$ inch. The connecting means described provides a method of obtaining a column of regularly spaced explosive cartridges.

Many equivalent modifications will be apparent to those skilled in the art from a reading of the above description without a departure from the inventive concept.

What is claimed is:

1. An explosive assembly comprising in column form a plurality of explosive cartridges in end to end relationship wherein the connecting means for at least two of said cartridges comprises a bail of a flexible material adhesively bonded to one end of each of said cartridges, and a wire connector having an open loop at each end of a straight portion, each loop containing one of said bails.
2. An assembly as claimed in claim 1 wherein said flexible bail comprises a length of cloth tape containing a pressure-sensitive adhesive.
3. An assembly as claimed in claim 1 wherein the end of each loop of the wire connector are beyond the beginning of the straight portion.
4. An explosive assembly consisting of a plurality of substantially cylindrical explosive cartridges joined end

to end by connecting means comprising a cartridge anchored ribbon loop joined by a connecting link having helical ends.

5. The structure of claim 4 wherein the helices are substantially parallel and lie in the same plane relative to the straight section of the connecting link.

6. The structure of claim 5 wherein the ends of the

helices lie on opposite sides of the straight section of the connecting link.
